PROCESS FOR THE ISOMERIZATION OF A
LOW-BOILING SATURATED HYDROCAR-
BONFrederick E. Frey, Bartlesville, Okla., assignor to
Phillips Petroleum Company, a corporation of
Delaware

Application October 5, 1942, Serial No. 460,867

15 Claims. (Cl. 260—666)

1

This invention relates to a catalytic process for reconstructing saturated hydrocarbons. More particularly it relates to the use of a catalyst which comprises a major proportion of concentrated hydrofluoric acid and a minor proportion of boron fluoride. This application is a continuation-in-part of my copending application, Serial No. 426,627, filed January 13, 1942, now U. S. Patent 2,403,649, issued July 9, 1946, which in turn is a continuation-in-part of my copending application Serial No. 323,443, filed March 11, 1940, now U. S. Patent 2,317,901, issued April 27, 1943.

The aforementioned copending application discloses that, in the presence of substantial proportions of hydrofluoric acid and under suitable conditions of time and temperature, saturated hydrocarbons are reconstructed to hydrocarbons of different carbon-skeleton arrangement and different boiling point. Paraffinic hydrocarbons, for example, undergo conversion to isomers and to hydrocarbons of both lower and higher molecular weights and correspondingly lower and higher boiling temperatures. I have found a marked improvement in the efficiency and utility of concentrated hydrofluoric acid as a catalyst for reconstructing hydrocarbons is brought about by including with it a minor proportion of boron fluoride.

An object of this invention is to improve concentrated hydrofluoric acid as a catalyst for reconstructing hydrocarbons.

Another object of this invention is to provide an improved catalytic process for isomerizing normal butane to isobutane.

Another object of this invention is to produce isobutane, isopentane, and isohexanes from normal pentane.

Another object of this invention is to produce isobutane and isohexanes from isopentane.

A further object of my invention is to effect a catalytic conversion of hydrocarbons.

Another object is to obtain conversion of a drastic type, with fracture of the carbon skeleton with consumption of only low and economical amounts of BF_3 as well as HF .

Other objects and advantages of this invention will be apparent from the accompanying disclosure and description and the accompanying drawing.

The present invention, broadly, comprises treating saturated hydrocarbons with concentrated, preferably anhydrous, hydrofluoric acid which contains, or which has had added to it, a minor proportion of boron fluoride to produce hydrocarbons of higher and/or lower molecular weights than the original hydrocarbons, together

2

with some isomers. By saturated hydrocarbons I intend to include paraffins and cycloparaffins, and by various modifications of my invention I can convert normal paraffins to isoparaffins, particularly those having more and/or fewer carbon atoms per molecule and, for cycloparaffins, I can change the number of carbon atoms in the ring, as in converting methylcyclopentane to cyclohexane and dimethylcyclopentane to methylcyclohexane. In one specific embodiment my invention comprises treating normal pentane with substantial amounts of liquid concentrated hydrofluoric acid, preferably essentially anhydrous hydrofluoric acid, to which has been added a minor proportion of boron fluoride to produce isobutane, isopentane and higher-boiling branched-chain hydrocarbons.

As disclosed and discussed in my above mentioned copending application Serial No. 426,627, several different types of chemical reactions may be involved in the process for reconstruction of hydrocarbons. The predominating reaction types, as deduced from a consideration of reactants, products, operating conditions, and theoretical aspects relating to the invention, may be exemplified as follows, as applied to saturated hydrocarbons:

35 The first two reactions, namely, reconstruction to produce both higher- and lower-boiling paraffins, and isomerization, respectively, predominate under relatively mild conditions. The yield of cyclohexane, exemplified in the third equation by 40 cyclohexane, is increased by increasing the temperature and/or the time of reaction. Several other types of reactions undoubtedly occur in the reconstruction process; however, the above-mentioned types appear to account for most of the 45 effects which are produced. The general term "reconstruction" is used herein to denote the production of one or more of the above mentioned effects and/or of other inherent advantageous effects which result from the practice of my invention.

Although the catalyst used in my process contains the same two ingredients as a catalyst previously proposed by Ipatieff and Pines for use as an isomerizing catalyst (U. S. 2,283,142 and 55 2,318,226), the two catalysts are by no means equivalent in composition, physical characteris-

tics, or activity. The catalyst of Ipatieff and Pines comprises a major proportion of boron fluoride modified by a minor proportion of hydrofluoric acid; it is used in a nickel lined reactor to increase its activity, and its active temperature range for isomerization of butane is 302 to 392° F. (150 to 200° C.). On the other hand my catalyst comprises a major proportion of hydrofluoric acid modified or activated by a minor proportion of boron fluoride; no nickel or other catalytic agent is required, and the reactions may be conducted at room temperature or at temperatures only slightly above room temperature. My catalyst, in its preferred form, is a homogeneous liquid solution of boron fluoride, or a hydrofluoric acid-boron fluoride complex, in a large excess of liquid hydrofluoric acid whereas the catalyst of Ipatieff and Pines appears to be a heterogeneous mixture comprising boron fluoride gas, a boron fluoride-hydrofluoric acid complex, which may be at least partly liquid under the prescribed operating conditions, and metallic nickel which is a solid. Essentially no free or uncombined hydrofluoric acid is present in the catalyst of Ipatieff and Pines.

An understanding of some aspects of the invention may be aided by referring to the accompanying drawing which is a schematic flow diagram of one arrangement of apparatus for practicing one modification of the invention. For the sake of concrete illustration, the description of the flow diagram will be limited to the reconstruction of normal pentane. The invention is, however, applicable to many other hydrocarbons and should be limited only as specified in the appended claims.

Normal pentane may be introduced through inlet 10 to reactor 11; concentrated hydrofluoric acid may be introduced through inlet 12, and a minor proportion of boron fluoride, through inlet 13. The liquid catalyst phase and the hydrocarbon reactant phase are brought into intimate contact, for example by emulsification, to effect reaction. The proportion of boron fluoride may be in the range of about 0.1 to about 30 per cent by weight of the hydrofluoric acid; usually it should be less than about 10 per cent. A proportion in the range of about 1 to 5 per cent is usually preferred because such a composition is a very active reconstructing catalyst at or slightly above room temperature, yet the proportion of added boron fluoride is sufficiently low that excessive costs for replacing and regenerating the catalyst are not incurred. In general the proportion of boron fluoride may be correlated with the reaction temperature, the maximum proportion being somewhat higher with decrease in temperature. In many instances it is desirable to add small amounts of boron fluoride at various times throughout the course of the reaction, as at a plurality of points along the length of a long reaction zone through which a stream of reactants is continuously passed. The relative proportions of catalyst and hydrocarbon are, within a wide range, not critical; good results are obtained using a hydrocarbon to catalyst ratio by weight in the range of about 0.1 to 3 or more, preferably it should be in the range of about 0.5 to 1.5, and in any event it is desirable to operate under conditions of temperature, pressure, and concentration such that appreciable amounts of a liquid hydrofluoric acid phase is present in the reaction zone. At very low or very high ratios, separation of the reaction products from the catalyst is difficult.

The reaction temperature for reconstructing

normal pentane may be in the range of about 0 to 400° F. and preferably the process is carried out in the range of about 125-250° F. At low temperatures the reaction rate is slow, whereas at high temperatures rate of spending of the catalyst or product degradation is excessive. In general the optimum reaction temperature is dependent upon the hydrocarbon material being treated. For reconstructing normal butane, and/or normal hexane, the temperature should be about 50 to 100° F. higher than for normal pentane.

The reaction time may vary from about 1 minute to two hours or more. The optimum time varies, in general, inversely with the reaction temperature. For temperatures within the above-mentioned preferred ranges the optimum time is ordinarily in the range of about 5 to 60 minutes. At very short times the conversion is incomplete, thus putting an unnecessarily heavy load on separating and recycling equipment, whereas at very long times, the undesirable secondary reactions occur and the life of the catalyst in terms of quantity of products per unit quantity of catalyst is short. Generally the time and temperature should be correlated to give about 70 to 90 per cent conversion per pass for reconstructing normal pentane; about 60 to 80 per cent per pass for reconstructing isopentane; about 50 to 70 per cent per pass for isomerizing normal butane; and 50 to 90 per cent per pass for reconstructing hexanes and/or heptanes.

As the catalyst and the reactant hydrocarbons are only slightly soluble in one another, especially at relatively low temperature, it is desirable to provide a means of agitation in reactor 11. The means for agitation may consist of stirrers, jet inlets, or baffles, or the reactor may be in the form of a tube of such dimensions that the flow of reaction mixture through it is turbulent. Rapid recirculation in a closed cycle, with continuous introduction of charge and withdrawal of effluents, may also be practiced.

The reaction mixture passes from reactor 11 through conduit 14 to separator 15 wherein by gravitational or centrifugal means and/or cooling it is separated into two liquid phases. The lighter or hydrocarbon phase, which contains a small proportion of dissolved hydrofluoric acid, may be passed through conduit 16 to fractionator 17. From fractionator 17 a mixture of hydrofluoric acid and low-boiling hydrocarbon material is distilled overhead and is recycled through conduit 18 to separator 15 and/or through conduit 43 to reactor 11. If any boron fluoride is present in the hydrocarbon phase passed through conduit 16, it is obvious that boron fluoride will also be present in the overhead fraction passed through conduit 18, since it is lower-boiling than hydrogen fluoride. Hydrocarbon material, free from dissolved hydrofluoric acid, is passed from the bottom of fractionator 17 through conduit 19 to deisobutanizer 20, wherefrom isobutane is distilled overhead and is withdrawn through outlet 21. The remaining hydrocarbon material is passed from the bottom of deisobutanizer 20 through conduit 22 to deisopentanizer 23, wherefrom isopentane is distilled overhead and is withdrawn through outlet 24. At least a part of this material may be passed, if desired, back to reactor 11 from conduit 24 through conduits 41 and 27. Hydrocarbon material from the bottom of deisopentanizer 23 is passed through conduit 25 to depentanizer 26, wherefrom normal pentane is

distilled overhead and is recycled through conduit 27 to reactor 11. Isohexanes and other normally liquid hydrocarbons are passed from the bottom of depentanizer 26 through conduit 28 to rerun column 29, wherefrom a major fraction suitable for blending in motor fuel is distilled overhead and is withdrawn through outlet 38. This fraction may be subjected to further fractionation and purification, if desired. A minor fraction of relatively high-boiling material is withdrawn through outlet 31. A fraction of intermediate boiling range may, if desired, be removed through conduit 42 and passed to conduit 27 and reactor 11.

Most of the heavier or catalyst phase from separator 15 is recycled through conduit 32 to reactor 11. Preferably, for purification or regeneration, part of it is passed through conduit 33 to purification equipment, illustrated by fractionator 34. From fractionator 34 substantially pure hydrofluoric acid is distilled overhead and is recycled through conduit 32 to reactor 11. Any free boron fluoride which is present in the catalyst passed through conduit 33 to fractionator 34 will, of course, also be present in the overhead fraction removed through conduit 32. High boiling material may be withdrawn through outlet 35; preferably however, it is passed through conduit 36 to heater 37. Heater 37 heats the material to a temperature in the range of about 100 to 600° F., usually more preferably in the range of about 350 to 500° F., whereupon fluoroorganic materials are decomposed, liberating HF. Some boron fluoride is also liberated. The heated and decomposed material then passes through conduit 38 to flash chamber 39, wherefrom hydro-

pending application Serial No. 769,980, filed August 21, 1947.

It will be appreciated that the drawing is only diagrammatic, and that suitable specific equipment for the practice of any modification of my invention may be readily designated and designed by one skilled in the art. Although the description of the drawing has been limited primarily to a description and discussion of the reconstruction of normal pentane, the same principles which are involved may be readily applied to a reconstruction of other specific saturated hydrocarbons or hydrocarbon fractions, such as fractions secured from natural or straight-run 15 gasolines, particularly the recycle of fractions of higher and/or lower boiling points, or ranges, than the hydrocarbon material in the net charge.

A few of the many aspects of my invention are 20 illustrated by the following examples, which are illustrative but not necessarily limitative of the invention.

Example I

A series of test runs for reconstructing hydrocarbons were made in a closed 18 liter steel reactor having a motor driven stirrer. The procedure was to charge predetermined quantities of anhydrous hydrofluoric acid, boron fluoride and hydrocarbon material to the reactor, to adjust the reaction temperature by means of a heated water or oil bath surrounding the reactor, to stir the mixture for a suitable reaction time, to withdraw the reaction mixture, to separate the hydrocarbon products from the catalyst, and to determine the composition and properties of the products. The following data were obtained:

Test no.	1	2	3	4	5	6
Hydrocarbon Charge						
BF ₃ , weight per cent of HF	n-pentane 2.7	n-pentane 2.9	n-pentane 3.5	iso-pentane 3.8	n-butane 2.8	n-butane 3.3

fluoric acid and boron fluoride are withdrawn overhead, and recycled through conduit 32 to reactor 11, and a high-boiling residue or sludge is withdrawn through outlet 40. Hydrogen fluoride may be introduced to conduit 36 and/or chamber 39 during the decomposition of the high boiling catalyst complex and polymer to increase the amount of BF₃ released in molecular form. This procedure for catalyst regeneration is more thoroughly described, and is claimed, in my co-

70 It is evident from this data that my invention is broadly applicable to the conversion of paraffin hydrocarbons to isomers and/or to hydrocarbons of higher and/or lower molecular weights. Recycling of undesired products may be employed to increase the ultimate yields of desired products.

Example II

In another test run, normal hexane and concentrated hydrofluoric acid to which has been

added 5.2 weight per cent boron fluoride were shaken together in a closed steel pressure vessel for 40 minutes. The temperature was maintained at 180° F. by an electric heater. The resulting hydrocarbon material was found to have the following composition:

Hydrocarbon:	Weight per cent
Butanes	0.5
Pentanes	0.6
Neohexane	6.5
Diisopropyl	7.9
2-methylpentane	24.9
3-methylpentane	10.5
Normal hexane	41.5
Heptanes and octanes	6.2
Heavier	1.4
	100.0

The total conversion in this run was 58.5 per cent of the original normal hexane. It is evident that the principal reaction occurring in this test run was isomerization of normal hexane to isohexanes including neohexane and diisopropyl. It is further evident from this test run that my invention, in one of its modifications, may be applied to the production of high yields of neohexane and diisopropyl from less highly-branched hexanes. Such a modification comprises reconstructing normal hexane and/or methylpentanes in the presence of concentrated hydrofluoric acid containing a minor proportion of boron fluoride, separating neohexane and/or diisopropyl from the resulting reconstructed hydrocarbon material, and recycling other hexanes and heavier hydrocarbons to the reconstructing step.

Example III

In another test run, normal hexane was reconstructed under conditions similar to those of Example II except that the temperature was 260° F. and the time was 35 minutes. The resulting hydrocarbon material was found to have the following composition:

Hydrocarbon:	Weight per cent
Propane	13.8
Isobutane	27.6
n - Butane	9.0
Isopentane	18.1
n - Pentane	4.5
Isohexanes	14.5
n - Hexane	3.9
Heavier	8.6
	100.0

The total conversion in this run was 96.1 per cent of the original normal hexane. The conditions for this run were more drastic than will usually be desired, since it is not usually desirable to produce such large proportions of propane. It is evident from this run however that at a somewhat lower temperature and/or a shorter reaction time high conversion of normal hexane to isobutane, isopentane, and iso hexanes may be obtained. To produce neohexane drastic conversion conditions are especially effective, and recycling to the reaction zone of C₄ and/or C₅ hydrocarbons, and if desired hexanes and other paraffin fractions boiling somewhat above neohexane; these hydrocarbons result as side products under neohexane-producing conditions.

A fresh feed conversion stock primarily pentanes, as in Example I, or hexanes or a mixture is also suitable for neohexane production.

It will be appreciated that various modifica-

tions of my invention may be practiced without departing from the spirit of the disclosure and discussion or from the scope of the claims.

I claim:

5. A process for converting normal pentane to other paraffin hydrocarbons including at least one isomeric pentane, which comprises subjecting a substantially saturated hydrocarbon material comprising normal pentane to the action of a catalyst consisting essentially of liquid concentrated hydrofluoric acid and boron fluoride in an amount between about 1 and about 5 per cent by weight of said hydrofluoric acid at a reaction temperature between about 100 and 250° F. under a pressure sufficient to maintain said hydrofluoric acid in liquid phase for a time sufficient to effect a conversion of at least 50 per cent of said normal pentane to other paraffin hydrocarbons including at least one isomeric pentane.

20. A process for converting normal butane to other paraffin hydrocarbons including isobutane, which comprises subjecting a substantially saturated hydrocarbon material comprising normal butane to the action of a catalyst consisting essentially of liquid concentrated hydrofluoric acid and boron fluoride in an amount between about 1 and about 5 per cent by weight of said hydrofluoric acid at a reaction temperature between about 100 and 250° F. under a pressure sufficient to maintain said hydrofluoric acid in liquid phase for a time sufficient to effect a conversion of at least 50 per cent of said normal butane to other paraffin hydrocarbons including isobutane.

25. A process for the production of neohexane from a paraffin hydrocarbon other than neohexane and containing from five to six carbon atoms per molecule, which comprises passing such a paraffin hydrocarbon to a conversion zone as the sole net hydrocarbon charge, charging also to said conversion zone paraffin hydrocarbons of lower molecular weight having at least four carbon atoms per molecule and recovered from effluents of said conversion, charging further to said conversion zone paraffin hydrocarbons of higher molecular weight and recovered from effluents of said conversion, contacting said paraffin hydrocarbons in said conversion zone at a conversion temperature with liquid hydrofluoric acid to which has been added not more than about ten per cent by weight of boron fluoride to effect a conversion of a large part of said net hydrocarbon charge to some other hydrocarbons including neohexane, recovering from effluents of said conversion zone neohexane so produced, recovering also paraffins of lower molecular weight and having at least four carbon atoms per molecule and returning same to said conversion zone, and recovering further low boiling paraffins of higher molecular weight and returning same to said conversion zone.

30. A process for converting normal pentane into isobutane, isopentane and iso hexanes, which comprises subjecting liquid normal pentane at a conversion temperature to the catalytic action of a liquid catalyst consisting essentially of concentrated hydrogen fluoride and boron trifluoride in an amount between about 1 and about 5 per cent by weight of said hydrogen fluoride and under a pressure sufficient to maintain said catalyst and said hydrocarbon as liquids for a time sufficient to effect a substantial conversion of normal pentane to isobutane, isopentane and iso hexanes, and subsequently recovering from effluents of said conversion a fraction comprising at least one of said isoparaffins so produced.

35. A process for isomerizing normal pentane

to produce isopentane, which comprises subjecting normal pentane to isomerization under isomerization conditions and in the presence of a liquid catalyst consisting essentially of concentrated hydrofluoric acid and boron trifluoride in an amount between about 1 and about 5 per cent by weight of said hydrofluoric acid and under a pressure sufficient to maintain said catalyst and said hydrocarbon as liquids to form isopentane, and recovering from effluents of said isomerization isopentane so produced.

6. A process for the conversion of a normal paraffin having from four to six carbon atoms per molecule to an isoparaffin having the same number of carbon atoms per molecule and an isoparaffin having a different number of carbon atoms per molecule, said different number of carbon atoms per molecule ranging from four to six, which comprises subjecting said normal paraffin with intimate mixing to the action of a liquid conversion catalyst consisting essentially of liquid hydrofluoric acid and boron trifluoride in an amount between about 1 and 5 per cent by weight of said hydrofluoric acid under conditions such that said catalyst and said normal paraffin are maintained as liquids and conversion of said normal paraffin to said isoparaffin is the principal reaction, and recovering from the reaction mixture isoparaffins so produced.

7. A process of isomerizing a normal paraffin having at least 4 carbon atoms per molecule, which comprises subjecting said normal paraffin to the catalytic action of 0.1 to 3 times its weight of liquid concentrated hydrofluoric acid as the effective catalyst, together with boron fluoride in an amount between about 0.1 and 10 per cent by weight of said hydrofluoric acid, at a reaction temperature in the range of about 0 to 500° F. and under a pressure sufficient to maintain said hydrofluoric acid and said hydrocarbon in liquid phase for a time sufficient to effect a substantial extent of isomerization of said normal paraffin.

8. A process for converting saturated hydrocarbons contained in a saturated hydrocarbon fraction by reactions comprising isomerization and disproportionation, said saturated hydrocarbon fraction containing at least one saturated hydrocarbon of at least 4 carbon atoms per molecule, which comprises subjecting said saturated hydrocarbon fraction to the catalytic action of 0.1 to 3 times its weight of intimately admixed liquid concentrated hydrofluoric acid, together with boron trifluoride in an amount in the range of about 0.1 to about 10 per cent by weight of the hydrofluoric acid, as the effective catalyst at a conversion temperature and under a pressure sufficient to maintain said hydrofluoric acid and said hydrocarbon in liquid phase for a time sufficient to effect a substantial conversion of saturated hydrocarbons contained in said hydrocarbon fraction into other saturated hydrocarbons including at least one isomer of a saturated hydrocarbon so converted, and subsequently recovering from effluents of said isomerization a hydrocarbon fraction comprising an isomer of said saturated hydrocarbon so produced.

9. A process for converting saturated hydrocarbons contained in a saturated hydrocarbon fraction by reactions comprising isomerization and disproportionation, said saturated hydrocarbon fraction containing at least one saturated hydrocarbon of at least 4 carbon atoms per molecule, which comprises subjecting said saturated hydrocarbon fraction to the catalytic action of 0.1 to 3 times its weight of intimately admixed liquid con-

centrated hydrofluoric acid together with boron trifluoride in an amount in the range of about 0.1 to about 10 per cent by weight of the hydrofluoric acid as the sole catalytic material at a conversion temperature and under a pressure sufficient to maintain said hydrofluoric acid and said hydrocarbon in liquid phase for a time between about 1 minute and about 2 hours and sufficient to effect a substantial conversion of saturated hydrocarbons contained in said hydrocarbon fraction into other saturated hydrocarbons including at least one isomer of a saturated hydrocarbon so converted, and subsequently recovering from effluents of said isomerization a hydrocarbon fraction comprising an isomer of said saturated hydrocarbon so produced.

10. A process for converting a paraffin hydrocarbon contained in a saturated hydrocarbon material into an isomeric hydrocarbon, which comprises subjecting a liquid saturated hydrocarbon material containing at least one low-boiling paraffin hydrocarbon of at least 4 carbon atoms per molecule to a conversion temperature in the presence of about 0.1 to 3 times its weight of intimately admixed liquid concentrated hydrofluoric acid together with boron fluoride in an amount in the range of about 0.1 to about 10 per cent by weight of the hydrofluoric acid as the essential catalyst under a pressure sufficient to maintain said hydrofluoric acid and said hydrocarbon in liquid phase for a time sufficient to convert said paraffin hydrocarbon into an isomeric hydrocarbon.

11. A process for converting a pentane into isobutane, an isomeric pentane, and isohexanes, which comprises subjecting a liquid pentane at a conversion temperature to the catalytic action of liquid hydrogen fluoride together with between about 0.1 and 5 per cent its weight of boron trifluoride as the essential catalyst under a pressure sufficient to maintain said hydrofluoric acid and said hydrocarbon in liquid phase for a time sufficient to effect a substantial conversion of said pentane to isobutane, an isomeric pentane, and isohexanes, and subsequently recovering from effluents of said conversion a fraction comprising at least one of said isoparaffins so produced.

12. A process for effecting disproportionation and isomerization of a low-boiling paraffin hydrocarbon having at least 5 carbon atoms per molecule, which comprises subjecting a liquid saturated hydrocarbon material comprising such a paraffin hydrocarbon at a reaction temperature not greater than about 250° F. to the catalytic action of about 0.1 to 3 times its weight of intimately admixed liquid hydrofluoric acid together with boron fluoride in an amount between about 0.1 and 5 per cent by weight of the hydrofluoric acid as the essential catalytic material under a pressure sufficient to maintain said hydrofluoric acid and said hydrocarbon in liquid phase for a time sufficient to effect isomerization and a substantial disproportionation of said paraffin hydrocarbon, forming paraffin hydrocarbons having fewer and more carbon atoms per molecule, and subsequently recovering from effluents of said reaction a fraction comprising at least one of said paraffin hydrocarbons so produced.

13. A process for the isomerization of a low-boiling saturated hydrocarbon having from four to six carbon atoms per molecule to produce an isomeric saturated hydrocarbon having the same number of carbon atoms per molecule while contained in a saturated hydrocarbon fraction, which comprises subjecting said saturated hydrocarbon fraction with intimate admixing to

the action of a liquid conversion catalyst consisting essentially of concentrated liquid hydrofluoric acid and boron trifluoride in an amount between about 1 and 5 per cent by weight of said hydrofluoric acid, the hydrocarbon to catalyst ratio by weight being in the range of about 0.1 to about 3, at a conversion temperature between about 0 and about 400° F. under a pressure sufficient to maintain said catalyst and said hydrocarbon as liquids and for a time between about 1 minute and about 2 hours and sufficient to effect a substantial amount of hydrocarbon conversion as evidenced by a substantial extent of change in the carbon skeleton of said saturated hydrocarbon having from four to six carbon atoms per molecule, and subsequently recovering from effluents of said isomerization a hydrocarbon fraction comprising an isomer of said saturated hydrocarbon so produced.

14. A process for isomerizing a low-boiling cycloparaffin hydrocarbon having at least six carbon atoms per molecule to produce a cycloparaffin having the same number of carbon atoms per molecule and a different number of carbon atoms in the nucleus while contained in a saturated hydrocarbon fraction, which comprises subjecting said saturated hydrocarbon fraction to isomerization under isomerization conditions in the presence of 0.1 to 3 times its weight of intimately admixed liquid concentrated hydrofluoric acid together with boron trifluoride in an amount between about 0.1 and 10 per cent by weight of the hydrogen fluoride as the essential isomerization catalyst under a pressure sufficient to maintain said hydrofluoric acid and said hydrocarbon in liquid phase for a time between about 1 minute and about 2 hours and sufficient to effect a substantial extent of conversion of said cycloparaffin hydrocarbon to a cycloparaffin hydrocarbon isomeric therewith, and recovering from effluents of said isomerization a hydrocarbon fraction comprising an isomeric cycloparaffin hydrocarbon so produced.

15. A process for isomerizing a low-boiling

cycloparaffin hydrocarbon having at least six carbon atoms per molecule to produce a cycloparaffin having the same number of carbon atoms per molecule and a different number of carbon atoms in the nucleus while contained in a saturated hydrocarbon fraction, which comprises subjecting said saturated hydrocarbon fraction to isomerization under isomerization conditions in the presence of an intimately admixed liquid catalyst comprising as the essential catalytic material concentrated hydrofluoric acid in an amount between about 0.1 and 3 times by weight of said hydrocarbon material together with boron trifluoride in an amount between about 0.1 and 5 per cent by weight of said hydrofluoric acid, for a time between about 1 minute and about 2 hours and sufficient to effect a substantial conversion of said cycloparaffin hydrocarbon to a cycloparaffin hydrocarbon isomeric therewith, and recovering from effluents of said isomerization a hydrocarbon fraction comprising an isomeric cycloparaffin hydrocarbon so produced.
